US00D990319S

(12) **United States Design Patent** (10) **Patent No.:** **US D990,319 S**
(45) **Date of Patent:** **** Jun. 27, 2023**

(54) **JUG**

(71) Applicant: **Leapfrog Product Development LLC**,
Chicago, IL (US)

(72) Inventors: **Micaela K. McCabe**, Chicago, IL (US);
Steven N. Pinelli, Ogden Dunes, IN
(US)

(73) Assignee: **Leapfrog Product Development LLC**,
Chicago, IL (US)

(**) Term: **15 Years**

(21) Appl. No.: **29/780,348**

(22) Filed: **Apr. 23, 2021**

(51) LOC (14) Cl. **09-01**

(52) U.S. Cl.

USPC **D9/531**; D9/537; D9/549

(58) **Field of Classification Search**

USPC D9/500, 501, 505, 544, 545, 549, 550,
D9/553, 554, 555, 556, 557, 558, 575;
D7/509, 510, 511, 523, 514, 530, 531,
D7/533, 537, 538

CPC B65D 1/0223; B65D 83/206; A45F 3/16;
A45F 2200/0583
